UNITED STATES PATENT OFFICE.

REGINALD A. FESSENDEN, OF BRANT ROCK, MASSACHUSETTS, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

ART OF SIGNALING BY ELECTROMAGNETIC WAVES.

1,080,271.

Specification of Letters Patent.

Patented Dec. 2, 1913.

Original application filed May 4, 1906, Serial No. 315,266. Divided and this application filed May 18, 1909. Serial No. 496,726.

To all whom it may concern:

Be it known that I, REGINALD A. FESSENDEN, a citizen of the United States, residing at Brant Rock, in the State of Massachusetts, have invented certain new and useful Improvements in the Art of Signaling by Electromagnetic Waves, of which the following is a specification.

My invention relates generally to wire- less telegraphy and more particularly to methods of tuning the circuit of the apparatus for selective reception of signals, as herein more fully described.

In the accompanying drawing forming a part of this specification, Figures I, II and III illustrate diagrammatically different combinations of elements of my improved apparatus and Figs. IV and V show in plan and section a variable transformer.

20 In the practice of my invention, I provide a capacity and inductance in shunt to each other and in operative relation to the aerial, and a receiver in operative relation to the condenser and inductance circuit.

25 The aerial 1 is grounded as at 2, and has a variable inductance 3 in series therewith. The aerial in Fig. I is also connected to inductances 4 and 6, in shunt to a condenser 5. The inductance 4 is preferably variable

30 and the inductance 6 forms the primary of a transformer having a secondary 7. Both 6 and 7 are preferably constructed so as to be capable of adjustment, as illustrated in Fig. IV. A receiver 8, telephone 9, poten-

35 tiometer 10, inductance 11 and condenser 12 are arranged in the circuit of the secondary 7. The condensers 5 and 12 are preferably adjustable, as is also the inductance 11. The aerial is preferably tuned to the frequency

40 of oscillations which it is desired to receive, and also the shunt circuit 4, 5 and 6, either alone or in conjunction with the secondary circuit 7, 12, 8 and 11. The circuit 7, 12, 8 and 11 is also preferably tuned to the frequency which it is desired to receive.

45 In the construction shown in Fig. II, the aerial 1, which is grounded as at 2, is connected in series with the inductance 14. The inductances 15 and 16, which are preferably adjustable, are shunted by the variable condenser 13. The receiver 19 is connected across the inductance 16. The cir-

cuit of the receiver 19 includes a variable inductance 18, an adjustable capacity 17, telephone 20, and potentiometer 21. Contact points *a* and *b* are adjustable.

55 The construction shown in Fig. III is especially applicable for use for the prevention of interference. The aerial 1 is grounded as at 2 and is connected to the variable inductances 3, 24 and 25. The aerial is also connected to inductances 27 and 28, which are arranged in shunt to the capacities or condensers 23 and 26. The inductances 27 and 28 form primaries 65 whose secondaries are shown at 29 and 30. In the circuit with these secondaries are included the variable inductance 31, adjustable capacity 36, receiver 34, potentiometer 35 and telephone or other indicating instrument 33. The transformers have preferably a variable ratio of turns, the construction shown in Fig. IV being conveniently used. The receiving system, with the exception of the circuit 1, 3, 25, 26, 28 and 2, is preferably tuned to the frequency which it is desired to receive, while this circuit is preferably adjusted empirically so as to cut out interference without weakening the received signals. Where, however, the sending station 80 emits waves of two frequencies, the one circuit 1, 3, 24, 23, 27, and 2 is preferably adjusted to one frequency, and the circuit 1, 3, 25, 26, 28 and 2 to the other frequency.

85 The variable transformer shown in Figs. IV and V consists of two pairs of drums 37, 38, and 39, 40, of which the drums 37 and 40 are preferably formed of metal or other conducting material, and are mounted in suitable bearings so as to be capable of rotation, 90 while the drums 38 and 39 are formed of insulating material, the drum 39 being rotatable within the drum 38 and adjustable in and out of the same by means of the threaded rod 41 passing through drum or cylinder 95 39. The drums 37 and 38 are made of the same diameter and are adapted to be driven simultaneously by suitable connection, as, for example, the sprocket chain 42, shown. The drums 39 and 40 are also of the same diameter and are connected by a sprocket chain 43 or other suitable means. The drum or cylinder 40 is also adjustable longitudinally by means of a screw 44. A portion of a

length of wire is wound on the drum 37, and another portion on the drum 38, and by rotating these drums the wire can be wound off of one and on to the other, and vice versa. 5 A length of wire is wound partially on the drum 39 and partially on the drum 40, and by rotating these drums the wire can be wound off of one and on to the other. It will be observed that as the wire is wound 10 off or on the drum 39, it is moved axially out of and into the drum 38, and that the coils on the drums 38 and 39 will form the members of a transformer which can be varied by rotating these drums in the manner stated. 15

I am aware that the use of a shunt resonant circuit for producing selectivity in electromagnetic apparatus is old. I am also aware that the use of a secondary 20 operatively connected to an inductance in parallel with a condenser is old, where the short circuited coil of a short circuited dynamometer operates as a secondary. And I am also aware that this arrangement has been used 25 in connection with an untuned aerial.

The interference preventer may be used with four branch circuits with a sending station emitting two frequencies, in this case 30 two of the branches are preferably tuned to the frequencies which it is desired to receive, and the other branches are used as balancing branches to cut out interfering signals.

This application is a division of my co-pending application No. 315,266, filed May

4th, 1903, (later issued as Patent No. 928,371, 35 of July 20th, 1909).

Having thus described my invention and illustrated its use, what I claim as new and desire to secure by Letters Patent, is the following:

1. In a wireless telegraphy, the method of tuning two circuits coupled by a transformer, which comprises varying the amount of wire in the coils of the transformer by infinitesimal increments and meanwhile adjusting the tuning in the two circuits to adapt the entire tuning to present conditions with respect to amount of energy transferred and closeness of tuning. 45

2. In wireless telegraphy, the method of 50 tuning two inductively coupled circuits by gradually altering the amount of wire in the coils of the transformer and simultaneously varying the coupling of the transformer.

3. In wireless telegraphy, the method of 55 tuning two inductively coupled circuits by varying both the coupling and the amount of wire in each coil of the transformer by infinitesimal increments, substantially, as described.

In testimony whereof I have hereunto signed my name this 11th day of May, 1909, in the presence of the two subscribed witnesses.

REGINALD A. FESSENDEN.
